FIRE EXTINGUISHER

Charles K. Huthsing, Clayton, Mo.

Application April 9, 1934, Serial No. 719,675

6 Claims. (CL 299—98)

This invention relates to fire extinguishers, and has special reference to portable fire extinguishers of the type in which a stream or jet of liquid is forcibly ejected from a container by a reciprocating double acting pump mechanism.

Heretofore portable fire extinguishers have usually included metallic containers for the liquid. Such containers have frequently or generally been made of brass and have been accepted and recognized for many years as standard fire extinguishers, although several objectionable features were inherent in their construction and it has been desirable to overcome these objections. Because of the nature of the liquid (carbon tetrachloride, a clear and colorless liquid) used in these fire extinguishers, the dependability and reliability of such extinguishers have been to a degree dependent and contingent upon inspection from time to time, and at proper times, to determine whether the liquid in the containers had evaporated or had been otherwise removed; therefore, since the dependability and reliability of such fire extinguishers has been contingent upon inspection from time to time, and at proper times, it has sometimes occurred that the fire extinguishers became undependable and unreliable because of neglect or oversight in making the time to time inspections at proper times. Furthermore, the metallic container walls of such fire extinguishers have on occasions become distorted or bent to such an extent as to prevent efficient and satisfactory operation of the ejector pump when the fire extinguisher was most needed. In addition, it has been necessary to inspect the interior of the metallic shell extinguishers for corrosion and such inspection required breaking of the soldered joints securing the tops to the containers, removal and subsequent replacement of the pump, all of which required the services of expert mechanics. In such fire extinguishers, the metallic walls are, of course, opaque and completely conceal the contents of the container from visual inspection without opening the container.

Objects of the present invention are to provide an improved fire extinguisher overcoming the foregoing stated objections and others by providing a transparent non-corrodible glass container filled with the liquid (carbon tetrachloride) which I color or stain in contrast with the glass container, so that said liquid must be consciously observed by anyone inspecting or even noticing the extinguisher, thus affording positive and constant indication of the amount of liquid in

the container; to provide a glass container that will withstand relatively severe shocks and that will not break easily even when placed on one end and overturned on solid supports, or when dropped limited distances onto hard objects or supports, and will thus meet with the existing high and rigid requirements, which are not met by easily breakable glass containers; to provide a cushioning device to receive and withstand shocks resulting from overturning the container onto solid supports; to provide a container whereby the pump mechanism therein may be observed and inspected when the container is not filled with contrastingly colored liquid that obscures the pump mechanism; to provide a glass container having an integral bottom wall strengthening and reinforcing the cylindrical wall of the container; to provide means for supporting the pump mechanism in connection with the bottom wall of the container and also in connection with the cap attached to the upper end and thereby distributing the weight of the pump mechanism and the strains and stresses exerted thereby when operated in such a manner as to provide a highly efficient and satisfactory extinguisher; and to provide a portable fire extinguisher embodying all of the improved features of construction herein disclosed or suggested, reference being made to the annexed drawings, in which—

Fig. 1 is a broken longitudinal diametrical sectional view of one form of the present invention.

Fig. 2 is a similar sectional view of a variation in the arrangement of the pump and discharge devices.

This application is a continuation in part of my prior application, Serial No. 686,355, filed August 23, 1933.

The invention shown in Fig. 1 of the drawings comprises a container including a side wall 1 and a bottom wall 2 integral with the side wall and both of non-corrodible material. In the specific embodiment shown, this container is of transparent glass that is characterized by a sufficient degree of infrangibility to withstand considerable shocks without breaking. For instance, the integrally united walls 1 and 2 may be made of transparent crystal glass and of sufficient strength to prevent breakage when stood on the lower end and overturned on and against solid supports or when dropped a limited distance on and against hard objects or supports or even when struck with considerable percussive force. The wall 1 may be formed with any desired number of integral surrounding beads or ribs 3 which

constitute spaced thickened portions of said wall 1.

The bottom wall 2 is upwardly convexed and on its under side is provided with an integral downwardly extended boss 4 and a bearing cavity 5 is formed in the inner side of the wall 2 above the boss 4. The boss 4 and the bearing 5 are at the center of the bottom wall.

A number of ribs 6 are formed integral with 10 the inner side of the wall 1 at the open upper end thereof and threads 7 are formed around the outer side of the wall 1 at the open end thereof above the uppermost bead or rib 3.

A metallic cap 8 has a cylindrical part 9 extending into the open upper end of the container. The marginal portion 10 of the cap 8 is seated against an elastic gasket 11 located against the end of the wall 1. A clamping fastener 12 is 15 screwed onto the threads 7 and has an inwardly extended marginal portion 13 clampingly engaging the marginal portion 10 of the cap 8 and thereby securely holding the cap clamped against the gasket 11 with sufficient pressure to provide a leak-proof joint.

25 The fastener 12 is formed with an outwardly extended bead 13' which is of larger diameter than and extends outwardly beyond the wall 1 and farther than the beads 3 and will receive and withstand shocks caused by overturning the 30 container onto solid supports or the like, and will also support the adjacent portion of the wall 1 above and out of contact with supports when the container is lying sidewise.

A reciprocating pump device, comprising a tubular piston rod 14 and a handle 15 attached to the outer end of said rod and provided with a discharge nozzle 16 opening into said rod, is operatively mounted in connection with the container. The rod 14 extends for sliding and turning 40 movements through a bearing 17 and a sealing device 18 in connection with the central portion of the cap 8, so that said rod 14 extends axially into the container. A pump cylinder 19 within the container has its upper end connected 45 with a member 20 mounted for turning movements on and about the rod 14 and being incapable of appreciable longitudinal movement. A corresponding member 21, attached to the lower end of the cylinder 19, is secured to a trunnion 22 having a flange 23 seating against the inner surface of the central portion of the bottom wall 2 of the container and has a portion 24 journaled in the bearing 5. Thus, the cylinder 19 is supported for free turning movements about 50 the longitudinal axis of the container and about the rod 14 and is prevented from substantial longitudinal movements. An inlet port 25, controlled by valves 26 and 27, opens into the upper end of the cylinder 19, and a similar inlet port 28, controlled by valves 29 and 30, opens into the lower end of the cylinder. The structure, including the ports 25 and 28 and containing the valves 26, 27, 29 and 30, extends laterally from the members 20 and 21 to points adjacent 55 to the side wall of the container, so that the liquid contents of the container will be drawn into the pump cylinder 19 through either of said ports which may be below the other port in the operation of the device.

70 The construction and arrangement shown and described, in which the open end of the glass container is strengthened and reinforced by the cap 8 and the clamping member 12 and in which the bearing 5 is formed in a reinforcing boss 4 in 75 connection with the bottom wall 2 of the con-

tainer and in which the pump mechanism has its upper end rotatively supported by the cap 8 and its lower end rotatively supported by and in connection with the bottom wall of the container, provides a strong and sturdy construction 5 that meets the known high tests and requirements and otherwise attains all of the indicated objects and purposes of this invention and overcomes the objections that have been herein suggested.

10 The transparent characteristic of the glass container permits ready inspection and observation of the mechanism therein when the container is empty, so that it is unnecessary to detach or remove the pump from the container in 15 order to make inspection from time to time and at proper times.

The liquid (carbon tetrachloride) contents of 20 the container may be and preferably are colored red, for instance, in contrast with the color of 25 the transparent container wall, so that positive information is afforded at all times as to whether or not the container is filled with liquid. Moreover, the visible colored liquid in the container is a warning that the stained or staining contents of the container should not be removed and used for cleaning purposes which often occurs in the case of devices at present in use and in which the containers are made of metal and the contents of the containers cannot be seen, 30 whether said contents are colored or stained or not. The stained or colored liquid in this environment functions to indicate need of replenishment arising from loss through deterioration of the device or otherwise and thereby indicates 35 need for repair of the device, functions not performed by the colored contents of thermometers or like instruments which substantially vary their levels under temperature changes.

40 The variation in the form of the invention shown in Fig. 2 from the form of the invention shown in Fig. 1 of the drawings involves a change in the construction of the pump mechanism whereby the jet or stream of liquid is discharged through the bottom wall of the container instead of through a nozzle attached to the operating handle.

45 The container includes a side wall 31 and a bottom wall 32 integral therewith and both of non-corrodible material. These walls are of transparent glass and are characterized by a sufficient degree of infrangibility to withstand, without breaking, the considerable shocks mentioned in describing the structure of Fig. 1. Said walls are of transparent crystal glass and the wall 31 may be formed with any desired number of integral surrounding beads or ribs 33 constituting spaced thickened portions of said wall 31. The wall 32 is upwardly convexed and on its under side is provided with an integral downwardly extended boss 34 having therethrough an opening 35. A nozzle or jet device 36 is mounted in the opening 35 and is secured therein by a clamping device comprising a nut 37 screwed into the inner end of the nozzle 36 and having on its inner end a flange 38 seated upon a gasket or washer 39 mounted in an enlarged recess 40 formed in the inner portion of the bottom wall 32. A tube 41 has its lower end extending through and secured within the nut 37 and opening into the 65 outlet orifice 42 of the nozzle.

70 A metallic cap 43 has a cylindrical part 44 extending into the open upper end of the container and interlocked with the ribs 33 to prevent the cap from turning with respect to the container, 75

the cap being clamped in rigid connection with the container by a clamping device 46 screwed on the external threads 47 at the open end of the container, and having a projecting shock receiving and withstanding bead 48 like the bead 13.

A tubular piston rod 48 is mounted for longitudinal and turning movements in a bearing 49 formed in connection with the cap 43 and through a seal device 50 supported by said cap. The tubular piston rod 48 extends centrally into the container. A pump cylinder 51 has its upper end attached to a member 52 mounted for turning movements on and about a piston rod 48 and its lower end attached to a member 53 provided with a bushing and bearing member 54 mounted for turning movements on and about the tube 41 and abutting against the inner end of the nut 37. The pump cylinder is thus supported for turning movements and is held from substantial longitudinal movements.

A valve controlled passage 55 opens through the member 52 into the upper end of the cylinder 51 and a like valve controlled passage 56 opens through the member 53 into the lower end of the cylinder 51. The structure in which these passages are formed extends laterally from the members 52 and 53 to points adjacent to the wall 31 of the container and adjacent to the end walls of the container, so that it is immaterial which end of the container is above the other. These valve controlled ports are the same as the valve controlled ports 25 and 28, and are similarly controlled.

35 A handle 57, attached to the outer end of the tubular piston rod 48, supports a seal device 58 for engaging and closing the open upper end of the tube 41 when the tubular piston rod 48 is in its unoperated position. The unoperated position of the tubular piston rod 48 is that in which a sealing member 59 is held seated against a rounded end 60 of the bearing 49. Operation of the pump forces the liquid into the open upper end of the tube 41, through said tube and out in 40 the form of a continuous jet or stream through the nozzle opening 42.

The pump mechanism shown in the drawings comprises an ejector piston 61 mounted for sliding movements in the cylinders 18 and 51 and operated by the tubes 14 and 48 in the manner described in my copending application, Serial No. 713,448, filed March 1, 1934.

The advantages of this construction are the same as the advantages mentioned in the description of the structure shown in Fig. 1 of the drawings and the objects of the invention are attained in substantially the same way. Thus, it is apparent that I may utilize many important features of my invention in an extinguisher discharging from the operating handle and also in an extinguisher discharging through the bottom wall of the container.

The construction and arrangement of the features of the invention may be varied within the scope of equivalent limits without departure from the nature and principle thereof.

I claim:

1. In a transparent container having therein a colored fire extinguishing liquid; a reciprocating tubular piston rod extending from within the container to the outside for conducting said liquid from said container without damaging said container, a discharge nozzle attached to the outer end of said rod, and means visible through 70 the wall of said container forming spaced pas-

sages within said container and near the opposite ends thereof for conducting said liquid to said rod irrespective of which end of said container is lower than the other.

2. In a transparent container having therein a colored fire extinguishing liquid; a reciprocating tubular piston rod extending from within to the outside of said container for conducting said liquid therefrom without damaging said container, a discharge nozzle attached to and opening into the outer end of said rod, means visible through the wall of said container forming spaced passages within said container and near the opposite ends thereof for conducting said liquid from the opposite ends of said container to said rod, means in connection with one end of said container supporting said rod and leaving said passage means visible through the wall of said container, and connections for pivotally supporting the ends of said passage means in connection with the opposite end of said container and with said rod respectively.

3. In a transparent container having therein a colored fire extinguishing liquid; a reciprocating tubular piston rod extending from within to the outside of said container for conducting said liquid from said container without damaging said container, a discharge nozzle attached to and opening into said rod, a device attached to one end of said container for supporting said rod, and means within said container and visible through the wall thereof forming spaced passages within said container and near the opposite ends thereof extending laterally from said rod to points adjacent to the wall of said container for respectively conducting into said rod liquid from that end of said container which is lower than the other.

4. In a transparent container having therein a colored fire extinguishing liquid; a reciprocating tubular piston rod extending from within to the outside of said container for conducting said liquid from said container without damaging said container, a discharge nozzle attached to and opening into the outer end of said rod, a device attached to one end of said container for supporting said rod, means within said container and visible through the wall thereof forming spaced passages within said container and near the opposite ends thereof extending laterally from said rod to points adjacent to the wall of said container for conducting into said rod liquid from that end of said container which is lower than the other, valves controlling said passages respectively, and means preventing simultaneous closing of said valves.

5. In a transparent container having therein a fire extinguishing liquid; means visible through the wall of said container forming spaced passages within said container and near the opposite ends thereof for receiving and conducting said liquid from the opposite ends of said container, a device pivoting and supporting one end of said means in connection with one end of said container, a reciprocating tubular piston rod extending through the opposite end of said container for receiving and conducting said liquid from said means to the outside of said container, a pivotal connection supporting the opposite end of said means on said rod and visible through the wall of said container, and a discharge nozzle attached to and opening into the outer end of said rod.

6. In a transparent container having therein a fire extinguishing liquid; means visible through the wall of said container forming spaced pas-

sages within said container and near the opposite ends thereof for receiving and conducting said liquid from the opposite ends of said container, a reciprocating tubular piston rod extending through one end of said container for receiving and conducting liquid from said passage means to the outside of said container and for pivotally supporting one end of said passage means, a discharge nozzle attached and opening 10 into the outer end of said rod, a device pivotally

supporting the opposite end of said passage means in connection with the opposite end of said container, valves for opening and closing said passage respectively, and means for holding open that valve which is lower than the other and leaving said other valve free to close while said passage means are visible through said wall of said container. 5

CHARLES K. HUTHSING. 10
